ATTORNEY

UNITED STATES PATENT OFFICE

ELIGIO BRAVO, OF SANTIAGO, CUBA

SANITARY CONTAINER FOR TOOTHPICKS

Application filed April 9, 1928. Serial No. 268,641.

This invention relates to a new and useful device in the nature of a sanitary container for tooth picks especially adapted for the purpose of holding tooth picks immune from dust and dirt and readily accessible to the user.

The object of the invention is to provide a sanitary container for toothpicks embodying certain new and novel features herein-10 after more fully described, claimed and illustrated in the accompanying drawing.

Fig. 1 is a perspective view of my improved sanitary container for toothpicks.

Fig. 2 is a transverse sectional view taken 15 on the line 2—2 of Fig. 1.

Fig. 3 is an enlarged fragmentary transverse sectional view illustrating in particular the hinge as embodied in my improved device.

20 Fig. 4 is a top plan view illustrating in particular a further development of my improved device.

Fig. 5 is a transverse sectional view taken on the line 5—5 of Fig. 4.

25 As here embodied my improved sanitary container for toothpicks embodies a container 10 or receiver of transverse semicircular concave section which is provided with closed ends 11 and 12, and an enlarged lower 30 central element 13, or base extended therefrom longitudinally, as a means of providing a suitable support for the said container. The container 10 is open at the top thereof, and has hinged thereto as at 14, 15, 16 and 35 17 a pair of cover members 18 and 19, extended from the sides of the said container and adapted to enclose or cover the open top of the said container. Expansion springs 20 are interposed and secured to the above 40 mentioned hinges 14, 15, 16 and 17, as a means of normally holding the said covers 18 and 19 in a horizontally extended or closed position. The above described construction is such as will permit the covers 45 18 and 19 to be hinged downwardly, as at 21 and 22 respectively, as a means of permitting toothpicks placed in the said container to be readily removed therefrom, and which will permit the said covers 18 and 19, to be 50 hinged upwardly, as at 23 and 24, respectively,

ly, as a means of permitting toothpicks to be placed in the said container 10.

In Figs. 4 and 5 of the accompanying drawing, I have shown rods 25 and 26 rotatively mounted in the brackets 27, 28, 29 and 30 secured to the ends 11 and 12 of the said container, and extended longitudinally thereof, in proximity to the above mentioned hinges 14, 15, 16 and 17 respectively. Plate members 31 and 32, rectangular shape are secured at their upper extremities to the rods 25 and 26 respectively, and are extended downwardly therefrom. The pinions 33 and 34 are mounted on the rods 25 and 26 respectively, at or near one extremity thereof, and mesh with the segment gears 35 and 36 respectively, which are provided with extended elements 37 and 38, secured to the above mentioned covers 18 and 19 respectively. The above described construction is such as will permit the plate members 21 and 22 to be pivoted upwardly as designated by the reference numerals 39 and 40, when the said covers 18 and 19 are hinged downwardly, as above set forth. The above described construction is such as will permit the plate members 31 and 32 when pivoted upwardly to force the toothpicks in the said container 10 to the center of the said container, which will allow the said toothpicks to be more readily and easily removed therefrom.

Having thus described my invention what I claim as new and desire to protect by Letters Patent of the United States is as follows:

1. A toothpick container of the class described embodying a container proper provided with a base element, a pair of covers hinged to the said container, said covers adapted to enclose the open top of the said container, and expansion springs as a means of normally holding the said covers in a closed position.

2. A toothpick container of the class described embodying a container proper provided with a base element, a pair of covers hinged to the said container, said covers adapted to enclose the open top of the said container, expansion springs as a means of normally holding the said covers in a closed

position, plate members operatively connected to the said covers as a means of allowing the toothpicks to be readily removed from the said container.

5 3. In a safety toothpick container of the class described, plate members secured to rods rotatively mounted in the said container, pinions secured to the said rods, said pinions adapted to mesh with segment gears 10 secured to the covers adapted to enclose the open top of the said container.

15 4. In combination with a safety container for toothpicks, plate members secured to rods, said rods rotatively mounted in the 20 said container, pinions secured to the said rods, said pinions adapted to mesh with segment gears secured to the covers adapted to enclose the open top of the said container and springs for normally urging the covers into closed positions for holding the plate members in lowered positions.

In testimony whereof I have affixed my signature.

ELIGIO BRAVO.
